Williamson Reif & Williamson

UNITED STATES PATENT OFFICE

FRANK V. BURMAN, OF ST. PAUL, MINNESOTA

IMPELLER FOR BLOWERS

Application filed February 3, 1930. Serial No. 425,438.

This invention relates to fans or impellers and has for an object the provision of a simple, highly efficient impeller which is perfectly balanced and centered and which will operate noiselessly.

It is a further object of my present invention to provide an impeller of the type having a multiplicity of circumferentially arranged blades wherein the body, frame and blades are integrally formed and accurately constructed from a single piece of material.

Most impellers used at the present time for ventilating systems, oil burners and analogous uses have been objectionably noisy, due to the fact that the balance and centering have not been perfect. Casting of an integral impeller including the frame and blades has been attempted and has been found entirely unsatisfactory, since the blades and other portions will vary somewhat in thickness and consequently in weight. Many impellers comprise a frame or body and a multiplicity of independent blades rigidly attached to the body. It is practically impossible in such structure to secure all the blades at the same angulation and the same distance from the center, and it is usually difficult to perfectly center the hub with reference to the body. Moreover, independently attached impeller blades, in many instances, become detached from the body or frame of the impeller due to the effect of centrifugal force and are projected through the air with much violence, often causing considerable damage.

A further object of my invention is to overcome the above noted objections and to provide an impeller, the body and blades of which are pressed from a single sheet of material, whereby the device will be perfectly centered and balanced and each blade identical in structure and angulation, since all blades are cut and pressed by the same die.

Another object is to provide a comparatively inexpensive and efficient impeller pressed from a symmetrical pan-shaped body, wherein the portions of the body between the several pressed blades will be entirely unobstructed to permit free passage of air.

Another object is to provide a simple effi-

cient method for making an integral impeller of the class above described.

These and other objects and advantages of the invention will be fully set forth in the following description made in connection with the accompanying drawing wherein like reference characters refer to similar parts throughout the several views, and wherein;

Fig. 1 is a front elevation of the intake of a blower having my impeller mounted therein;

Fig. 2 is a vertical section taken on the line 2—2 of Fig. 1;

Fig. 3 is a detail view showing a fragment of the impeller in front elevation;

Fig. 4 is a fragmentary side elevation of my impeller detached, a portion of the reinforced and turned outer edge of the body being broken away; and

Fig. 5 is a side elevation illustrating the step of my method, which consists in longitudinally slitting a symmetrical perfectly centered pan-shaped body.

As shown in the drawing, my impeller is mounted in a conventional blower casing, comprising telescoped shell sections 5 and 6, said shell sections being constructed to afford a spiral passage surrounding the blower and terminating in a discharge 7. The shell sections 5 and 6 are rigidly secured to a base 8 by suitable means, such as a pair of angle brackets 9 and 10, spot-welded or otherwise rigidly connected with base 8 and with the exterior of the shells. Shell member 5 carries a symmetrical converging intake casing 11, which, as shown, is provided with an outwardly projecting annular lip 11a. A suitable electric motor M is mounted rearwardly of the shell 6 and secured to base 8 by a bracket 12, the armature shaft 13 of said motor being axially aligned with the intake casing 11 and projecting within the center of the housing formed by shells 5 and 6. My impeller is fixed to armature shaft 13 and disposed substantially centrally of the blower casing and concentrically with the intake casing 11 and directly therebehind.

My impeller is constructed from a single sheet or disc of material, such as sheet metal and the material is first pressed or spun to

form a perfectly symmetrical pan-shaped body; preferably being tapered from its edge to its base. The base 14 of my impeller is provided with a perfectly centered circular hub-receiving aperture 14a and a series of relatively small circumferentially spaced attachment apertures (as shown, four in number) surrounding said hub-receiving aperture. If the body is die-pressed, the base is 10 preferably formed flat by the die and the hub-receiving aperture and attachment apertures are precisely positioned and formed by the die in the pressing operation.

The body so formed is next preferably 15 placed on a spinner and the base 14 is spun in the shape of a cone projecting inwardly toward the peripheral edge of the body. During the spinning operation, I also prefer to turn the edge of the body into a reinforcing bead X. It will, of course, be understood that my method is not limited to the step of spinning the base or die-pressing the body, but that the pan-shaped body may be formed 20 from sheet material by any suitable means whereby the body is perfectly balanced, symmetrically formed and the hub-receiving aperture perfectly centered.

The pan-shaped body so formed is next progressively rotated and at each rotative step 25 a suitable die slits the body longitudinally from a point adjacent its rim to a point adjacent its base and simultaneously presses inwardly a relatively narrow portion of the stock to form one of the blades 15, the angulation 30 of the blades being determined by the shape of the die and the width of the blades being determined by timing and actuating mechanism for progressively rotating the body before each operation of the die. The 35 blades are of concave-convex cross section with their concave sides disposed inwardly of the body and are so formed in the step of my method above described. In the steps of forming the blades, the material at the connected ends of the blades is drawn by the die 40 so that it will not break or separate but will leave curved webs 15a and 15b at the ends of the blades. The material of the body is 45 only severed along straight lines extending longitudinally of the body and circumferentially thereof. After the blades are slit and pressed out, the body may be progressively run through the die again to perfect the 50 shaping of the blades and their inclination.

55 The portions of the body between two slits are skewed by the die or angled with respect to the peripheral edge of the body, and since they are pressed and die-made each one will be a perfect replica of the other.

60 A hub is formed for the body and is preferably made on a screw machine to insure perfect symmetry, balance and centering. This hub includes a heavy sleeve which is provided with a threaded radially extending 65 channel in which a set screw is disposed for

fixing the hub to the motor shaft 13. The hub also carries a symmetrical truncated conical flange or skirt which has an annular abutment shoulder adjacent its restricted end and this skirt precisely fits the restricted portion of the truncated conical base of the impeller body, the peripheral edge of the apertured portion of said base abutting the shoulder and the base being secured to the flange or skirt by suitable means, such as bolts or rivets 16 which extend through the attachment apertures in base 14.

70 From the foregoing description it will be seen that a very perfect impeller can be made from sheet material at exceedingly low cost, 80 and that the angulation of the multiplicity of blades, as well as the weight and shape of the blades, will be identical since the impeller is die formed. It further will be apparent that the impeller will be perfectly centered, and consequently will operate efficiently and practically noiselessly, and can never throw a blade.

75 One of the most important features of my invention is that the body of the impeller is comparatively unobstructed, thereby effecting the displacement of a relatively great amount of air in comparison with other impellers of the Sirocco type. It will be noticed that no material of the body extends between the blades nor are the blades provided with any flanges or other obstructions at their longitudinal edges. This is due to the fact that the blades are slit longitudinally from the material of the body and the slit portions 100 turned on their longitudinal axes, the only connections of said blades with the body being the webs 15a and 15b at their extremities. As has been stated, the material of the body is only severed along straight lines extending longitudinally thereof and the material is drawn at the ends and no rib or reinforcement member obstructing the passages between the blades is necessary to support the same. The passage of air radially and outwardly of the impeller is only obstructed by 105 the thickness of the sheet material, which is almost negligible.

110 Due to the structure and advantages above described, my impeller has been found to have much greater capacity and efficiency than other sheet-metal impellers known to me at this time.

115 It will, of course, be understood that various changes may be made in the form, details, arrangement and proportions of the parts without departing from the scope of my invention.

120 What is claimed is:

1. An impeller comprising a symmetrical rim constructed of sheet metal and provided with a series of longitudinal slits intermediate its edges, the portions of said rim between said slits being bent out of the curve 125 of said rim providing spaced blades connected 130

with the rim only at their ends, the ends of the bent portions between said longitudinal slits being uncut and drawn in said bending to form triangular-shaped ends for the blades 5 angled with respect to the main portions of the blades and bent out of the periphery of the rim.

2. An impeller comprising a symmetrical annular rim constructed of sheet metal and 10 provided with a series of longitudinal slits intermediate its ends, the entire portions of the material of said rim between said slits being bent out of the curve of said rim to provide spaced blades connected with the rim 15 only at their ends, the ends of said blades being integrally connected with said rim throughout their entire widths and being drawn in the bending of said blades to form triangular-shaped connection portions angled 20 with respect to the main portions of the blades and bent out of the periphery of the rim.

In testimony whereof I affix my signature.
